B. DOUGLAS.
COOK STOVE.

Patented June 30, 1836.

June 30, 1836

Boriah Douglas, of Albany, New York,
Letters Patent.

The schedule referred to in these Letters Patent and making part of the same, containing a description in the words of the said Boriah Douglas, himself of his improvement in the ornamental Parlor Stove.

Be it known that I, Boriah Douglas, of the city & County of Albany, and State of New York, have invented an improvement in the useful arts, being an ornamental parlor stove, which is described as follows, referring to the annexed drawings of the same making part of this specification. This parlor stove consists of a central cast iron plate A, of about fifteen inches in diameter placed horizontally on legs four inches high, grooved in the upper margin forming the bottom of the recesses, or ash box, covered plates B, in segments one inch high are made to stand upright all around in the groove just mentioned, except a space for the door C, to take out the ashes. Another plate D, of the same size and grooved to correspond with the lower one exposes the side pieces and forms the top of the ash box. The centre of this plate is cut out for the grate E, to let in, over which is erected the cylindrical firebox F, which is about eleven inches high. The upper margin of the top of the ash box being grooved, sections of a curved plate G, of the same height of the firebox, perforated all round in a tasteful manner are set upright in said groove. Another iron plate H, grooved in the under edge to correspond with the groove in the middle plate below is placed on top of the curved pieces the upper ends of which enter the grate E. Holes are bored into the under side of the upper plate and down inside of the perforated plates through the lower plates and fastened with screws confining the whole together. The centre of the top plate is cut out to receive the top of the firebox, over which

June 30, 1836

which is placed a collar b, forming a flue made in the same man
ner as those on the cooking stove patented by me. The shaker or poker
to clean the grate from ashes is made in the same manner as the one in
my cooking stove. The back side of the collar is left a hole d, in the plate
sufficiently large to pass the hand through the same to clean the stove.
Another similar hole is made in the top of the ash box into which
the dirt around the cylinders may be swept. The cover designed
to fill the holes in the top plate are perforated with apertures
The remainder of the plate also is perforated in any manner to suit the
purpose of the constructor. The use of these perforations or open work
is around and over the fire box is to facilitate the diffusion of
heat, to give the glazing appearance of the inner cylinders when
red hot; and give to the stove symmetrical proportion and beautiful
appearance. What I claim as my invention and which I desire
to secure by Letters Patent, consists in the combination and
arrangement of the several parts of the before described ornamental
parlour stove, particularly the perforated plates surrounding
the fire box. In testimony whereof I have hereunto set my
hand this twenty third day of May A.D. 1836.
